UNITED STATES PATENT OFFICE.

JUDIA E. STOVALL, OF CLEVELAND, OHIO.

DESIGN FOR A FLAG.

Application filed October 17, 1924. Serial No. 11,105. Term of patent 14 years.

To all whom it may concern:

Be it known that I, JUDIA E. STOVALL, a citizen of the United States, residing at Number 3017 East 82nd Street, Cleveland, in the county of Cuyahoga and State of Ohio, have invented a new, original, and ornamental Design for Flags, of which the following is a specification, reference being had to the accompanying drawing, forming part thereof.

The figure is a plan view of a flag, showing my new design.

I claim:

The ornamental design for a flag, as shown.

JUDIA E. STOVALL.
